D-888

John S. Gallagher junr.

Design

For Lohorn, Egg Beater and Agitator.

Patented May 19-1857.

Ms. 888

John J. Gallagher, Jr. of Washington, D. C.
Letters Patent No. 888, Dated May 19, 1857.

The schedule referred to in these Letters Patent, and making part of the same.

To all whom it may concern:

Be it known, that I, John J. Gallagher junior, of the city of Washington in the District of Columbia, have invented and produced a new and original design for Columns, Egg Beaters, and Whip Agitators; And I do hereby declare that the following is a full and exact description of the same, and as represented by the accompanying drawings.

Figure 1, being a perspective view of the design complete.

Figure 2, being the top of the design detached, showing the internal configuration of the design.

The features of my design is the making a Column, Egg-Beater, or Whip Agitating Vessel, of metal or other material, with an ornamental base and pedestal 2, 2, 2, 2, surmounted on which is a concavo-convex, ribbed, or scallop-like bottom part b, b, b, b, attached thereto, and rising therefrom, is a concavo-convex, ribbed or fluted vessel, the ribs or flutes, c, c, c, c, c, being vertical.

The upper extremity of the vessel part, is surmounted by a sloping, bevelled or flaring rim or band d, d, d, d, in which is designed to fit the covering or top of the vessel. The said top being shaped so as to conform to the inner circumference of the rim, and to rest on the projecting parts formed by the upper termination of the vertical ribs or flutes.

2

Des. 888

To make a more ornamental vessel, fluted or swaged bands for hoops are affixed at suitable places around the outside circumference as at e, e, e, e. To the bottom of the vessel, extending outwardly horizontally, is a spigot or faucet device f, f, and on the sectional top Fig. 2, is inserted a plate of glass, beneath which for preservation and ready observation, is the label of directions as shown at g, g. To the other sectional part of the top is attached an ornamental standard or bearing h, h, h, formed at its upper part in shape of an arch, surmounted by an acorn i, and the end of the arched part terminating in a head or swelled part j.

Having described and shown the novel features of my design, what I claim as of my own invention and production and desire to have secured by Letters Patent of the United States, is specifically as follows, viz:

I claim the general configuration of the vessel, as shown in Figure 1, with the ornamental standard or bearing h, i, j. Substantially as shown, described, and for the purposes set forth.
